William Fitchard

UNITED STATES PATENT OFFICE.

JAMES REID, OF NEW YORK, N. Y.

UMBRELLA.

Application filed August 24, 1922. Serial No. 533,964.

This invention relates to umbrellas of the so-called emergency type usually employing a cover constructed from waterproof paper or some similar inexpensive material.

- 5 An important object of the invention is to provide a generally improved umbrella of the class mentioned, which is strong, durable, compact and inexpensive to manufacture.
- 10 Other objects and certain advantages of the invention will become apparent from the following description when taken in connection with the accompanying drawings, in which—

15 Figure 1 is a plan view of an umbrella embodying my invention.

Figure 2 is a horizontal substantially central sectional view of Figure 1.

20 Figure 3 is a somewhat enlarged fragmental sectional view similar to that of Figure 2.

Figure 4 is a sectional view taken on line 4—4 of Figure 3.

25 Figure 5 is a sectional view taken on line 5—5 of Figure 3.

Figure 6 is a sectional view taken on line 6—6 of Figure 3.

Figure 7 is a sectional view taken on line 7—7 of Figure 3.

30 Figure 8 is a more or less diagrammatic view illustrating the manner in which the cover sections are cut from a strip of material.

Figure 9 is a sectional view illustrating 35 the manner in which the cover sections are attached to the umbrella ribs and to each other.

Figure 10 is a view similar to that of 40 Figure 9, illustrating a slightly modified manner in which the cover sections may be attached to the ribs and to each other.

Figure 11 is a fragmental perspective view 45 showing adjacent portions of the cover sections as being rolled one upon the other when the umbrella is collapsed.

In the drawings, wherein for the purpose 50 of illustration is shown what I at present consider the preferred form of my invention, the numeral 5 indicates a multi-faced stick or handle which is preferably square in cross section and for certain economical reasons constructed from wood. Inasmuch 55 as the stick is square in cross section, I am enabled to utilize the same to prevent turning thereupon of a peculiarly constructed

runner hereinafter more particularly described.

To the upper end of the stick, there is connected a sleeve 6, which is so formed as to provide ribs or shoulders 7, having seated thereon a plate 8, which is held in position upon the sleeve 6 by reason of the fact that the upper end of the sleeve is clinched over into locking engagement therewith, as shown at 9. The plate 8 is provided with a plurality of ears 10, which are folded alternately in opposite directions about a hinge band or ring 11. These ears serve not only as a means for effectively locking the hinge band or ring 11 in position upon the plate, 65 but function also as spacers for the several hinge members 12, carried respectively by the plurality of ribs 13. The hinge members 12 are constructed from a suitable inexpensive material, and are provided with longitudinally disposed flanges 13', carrying ears 14, which are adapted to be depressed or embedded into the opposite faces of the ribs, thereby rigidly securing the hinge members to the several respective ribs. The 70 hinge members 12 are also provided with inwardly projecting straps 15, which are folded around the band or ring 11, intermediate the several ears 10, thus hingedly connecting the several ribs 13 with the band 75 or ring 11.

To the several ribs 13 there are connected a corresponding number of stretchers 17, by means of hinges indicated as a whole by the numeral 18. These hinges comprise hinge plates 19, the longitudinal edges of which are folded over to provide flanges 20, carrying ears 21, driven or embedded into opposite faces of the ribs, thus rigidly attaching the several plates 19 to their respective ribs. The 80 plates 19 are so constructed as to provide, at their inner ends, depending straps 22, which are folded about a plurality of yokes 23, carried at the outer ends of the stretchers 17. These yokes are preferably constructed from 85 wire and are bent at opposite ends to provide points 24, adapted to be driven or embedded into the stretchers 17, as a means for securing the several yokes in their proper positions. These yokes may be further anchored to their respective stretchers by means of encircling bands 25 passed around the stretchers 17 as most clearly shown in Figures 1 and 7. Upon the stick 5, 90

100 there is arranged a slideable runner 26; which 105

110

comprises a metallic sleeve 27 so constructed as to conform with the contour of the stick, as clearly shown in Figure 5. The sleeve 27, at its upper end, is provided with a rib or bead 28, upon which is seated a plate 29, the plate 29 being held in position upon the bead 28 as a seat by reason of the fact that the upper end of the sleeve 27 is clinched into locking engagement therewith, as shown at 10. This plate is similar to the one indicated by the numeral 8 and hereinbefore described and is so constructed as to provide a plurality of arms 31, and a plurality of keepers 32. The arms 31 are folded about a hinge ring 15 or band 33 in one direction, whereas the keepers 32 are folded about the band in an opposite direction. The keepers 32 function not only, in connection with the wings 31, as a means for retaining the band 33 in a correct 20 position, but serve also as seats for the hinge ends 34 of the several hinge plates 35 carried by the stretchers 17. These hinge plates are similar to the plates 19, hereinbefore described, and are so constructed as to provide 25 a plurality of ears 37 adapted to be driven or embedded into opposite faces of the several stretchers, thus permanently anchoring the plates to the stretchers to provide a strong and reliable connection of the same 30 with the runner 26.

As a means for retaining the runner 26 in the position shown in Figure 3, and to maintain the umbrella extended, I provide the usual form of spring latch 38, which is carried by the stick 5, and so connected thereto as to permit the runner 26 to move freely over the same when it is desired to collapse the umbrella.

As a covering for the umbrella frame, the 40 elements of which have been previously described, I employ some suitable inexpensive material, such as waterproof paper, a strip of which is indicated by the numeral 39. To form the cover, indicated by the numeral 40, the strip of paper 39 is so cut as to provide 45 a plurality of approximately triangularly shaped segments 41, without any substantial loss of material. In applying the segments to the umbrella frame, corresponding margins thereof are adhesively attached to the under and side faces of the ribs 13 throughout their lengths, whereas the opposite corresponding margins of the segments are so positioned as to overlie the upper faces of 50 the several ribs and the adjacent sections. The overlying portion 42 of one segment is adhesively attached to the folded portion 43 of the adjacent section and is likewise adhesively connected by means of a waterproof 55 glue or adhesive to the upper faces of the ribs 13. By this method of attaching the sections to the ribs and to each other, the several ribs are materially reinforced, due to the fact that they are completely enclosed by 60 the folded and overlying margins of the sev- 65

eral sections 41. Not only are the several ribs materially reinforced by the construction which I employ, but the sections 41 are themselves reinforced to a considerable extent at their point of connection with the 70 ribs by reason of the fact that the relatively large overlying areas or portions 42 and 43 are adhesively attached to each other.

By reinforcing the ribs, as above set forth, I am enabled to use, in their construction, 75 cheap, light material, such as wood, which in itself would be too weak to stand the strains to which it would necessarily be subjected in use.

In the modified form of my invention, 80 shown in Fig. 10, the sections 41 are at their corresponding edges folded completely around the several ribs, as shown at 44, and are adhesively attached to all four sides of each rib, thereby completely enclosing the 85 same, whereas the opposite margins 45 of the sections are adhesively attached to the adjacent sections in a manner similar to that hereinbefore described. It will be appreciated that while the sections 41 are attached 90 to the several ribs in a manner slightly differing from that hereinbefore described in connection with Figures 1 to 9, inclusive, the same or substantially the same reinforced effect is obtained.

In constructing the umbrellas embodying either form of my invention, above described, the outer margins of the several sections 41 comprising the cover are so folded upon themselves as to provide a reinforcing edge 100 46. This reinforcing edge not only protects the outer margin of the cover from undue tearing, such as might result from the careless handling of the umbrella, but also serves as a means for reinforcing the cover against 105 such lateral or tensile strains as may be set up therein, particularly at or near the periphery thereof by the several ribs when extended.

With umbrellas, particularly of the class 110 to which my invention relates, a highly important factor to be considered is collapsibility and to facilitate collapsing of the umbrella into a highly compact unit, I, as will be readily appreciated, have so connected 115 the several stretchers 17 to the plate 29 as to provide sufficient clearance between the sleeve 6 and the inner ends of the ribs 13 to permit their being readily moved into a parallel or substantially parallel relation with respect to the stick. Furthermore, by reason of the peculiar hinge connections between the ribs 13 and stretchers 17, the ribs and stretchers are permitted to assume a parallel or substantially parallel relation 120 with respect to the stick when the umbrella is collapsed, and likewise the several stretchers, due to their peculiar form of connections with the runner 26, are permitted to move into proximity to the stick and assume a 125 130

parallel or substantially parallel relation thereto. It may be remarked that this complete collapsing is obtained freely and easily, in so far as the several hinge connections is 5 concerned, without setting up any undue strain within the several hinge elements, and other members cooperating therewith.

In order to further facilitate collapsing of the umbrella, I, in forming the several sections 41, have so creased the same, as shown 10 at 47, that adjacent portions thereof tend to curl, one upon the other, as illustrated in Figure 11. This tendency toward curling is due to the fact that the creases 47 are not 15 struck from a central point intermediate the outer ends of the ribs to the center of the cover, but from a point a little to one side of the center, to the center of the cover. By this arrangement, it will be appreciated that 20 since the distance A, for example, is greater than the distance B, the corresponding portions C of the several sections 41 will tend to override the portion D of the sections upon movement of the outer ends of the ribs 25 toward each other in collapsing the umbrella, thus enabling the same to be folded in a neat and compact unit.

Having thus described my invention, what I claim is:

30 1. An umbrella comprising a stick, a plurality of ribs hingedly connected to said stick, and a cover carried by said ribs, said cover being in the form of a plurality of sections having their corresponding margins folded around said ribs and adhesively attached thereto and their opposite corresponding margins overlying adjacent sections and in flat contact therewith at their point of connection with said ribs.

40 2. An umbrella comprising a stick, a plurality of ribs hingedly connected to said stick and a cover carried by said ribs, said cover being in the form of a plurality of sections having their corresponding margins folded around said ribs and their opposite corresponding margins overlying adjacent sections and in flat contact therewith at their point of connection with said ribs, said sections being adhesively secured to said ribs substantially throughout their lengths and attached to each other in proximity to their point of connection to said ribs.

50 3. An umbrella comprising a multi-faced stick, ribs hingedly connected to said stick, stretchers hingedly connected to said ribs, a runner slidable on said stick, said runner having a plurality of faces adapted to cooperate with faces of said stick to retain said runner against rotation with respect to said stick, and means for connecting said stretchers to said runner.

55 4. An umbrella comprising a stick having a square cross sectional area, ribs hingedly connected to said stick, stretchers hingedly connected to said ribs, a runner slidable upon

said stick, said runner having a plurality of faces adapted to cooperate with sides of said stick to retain said runner against rotation with respect to said stick, and means for connecting said stretchers to said runner. 70

5. An umbrella comprising a stick having a square cross sectional area, ribs hingedly connected to said stick, stretchers hingedly connected to said ribs, and a runner slidable upon said stick, said runner having a plurality of faces corresponding in number to the number of faces of said stick and adapted to cooperate with the sides of said stick to retain said runner against rotation with respect to said stick, and means for connecting said stretchers to said ferrule. 75

6. An umbrella comprising a stick, a plurality of ribs hingedly connected to said stick, and a cover carried by said ribs, said cover being in the form of a plurality of 80 sections, each of said sections having a crease formed therein along a radial line extending from the central portion of said cover to the outer margin thereof unequi-distant from adjacent ribs to facilitate folding of 85 adjacent portions of said sections one upon the other when the umbrella is collapsed.

7. An umbrella comprising a stick, a plurality of ribs hingedly connected to said stick, and a cover carried by said ribs, said cover being in the form of a plurality of sections having corresponding margins folded around said ribs and attached thereto and provided with creases extending from the central area of said cover to a point 90 on the outer margin thereof unequi-distant from the outer ends of said ribs to facilitate folding of adjacent portions of said sections one upon the other when the umbrella is 95 collapsed. 100

8. An umbrella comprising a stick, a plurality of ribs, hinge plates carried by said ribs, said hinge plates having portions thereof embedded into said ribs, and means for hingedly connecting said hinge plates to 105 said stick.

9. An umbrella comprising a stick, a plurality of ribs, horizontal plates carried by said ribs, said horizontal plates having portions thereof embedded into said ribs, a sleeve carried by said stick, a plate associated with said sleeve, said sleeve having an end thereof upset into engagement with said plate whereby said plate is locked in position with respect to said sleeve, a hinge ring, ears carried by said plate, alternate ears of said plate being bent over said ring in opposite directions whereby said ring is locked in position with respect to said plate, and means for connecting said hinge plates to 115 said ring. 120

10. An umbrella comprising a stick, a plurality of ribs, a plurality of stretchers, hinge plates carried by said stretchers, a runner carried by said stick, a plate associated with 130

said runner and provided with ears, a hinge ring associated with said plate, certain ears of said plate being bent over said ring in opposite directions to hold said ring in position with respect to said plate, and means for hingedly connecting said hinge plates with said ring.

11. An umbrella comprising a stick, a plurality of ribs, hinge plates carried by said ribs, a plate carried by said stick and provided with ears, a hinge ring, certain ears of said plate being bent around said ring in opposite directions to hold said ring in position with respect to said plate, and means for hingedly connecting said hinge plates to said ring.

12. An umbrella comprising a stick, a plurality of ribs, hinge plates carried by said ribs, a plate carried by said stick and provided with ears alternately disposed in opposite directions, a hinge ring locked in position upon said plate by said ears, and means for hingedly connecting said hinge plates to said hinge ring, said hinge plates being retained in a spaced relation by said ears.

13. An umbrella comprising a stick, a plurality of ribs hingedly connected to said stick, a runner slideable upon said stick, a plurality of stretchers hingedly connected to said runner, hinge plates having portions thereof embedded in said ribs, yokes carried by said stretchers, portions of said yokes being embedded in said stretchers, and means for hingedly connecting said yokes to said hinge plates.

14. An umbrella comprising a stick, a plurality of ribs hingedly connected to said stick, a runner slideable upon said sticks, a plurality of stretchers hingedly connected to said runner, hinge plates having portions thereof embedded in said ribs, yokes carried by said stretchers, said yokes having portions thereof embedded in said stretchers, retaining elements in the form of bands for anchoring said yokes to said stretchers, and means for hingedly connecting said yokes with said hinge plates.

15. An umbrella comprising a stick, ribs

hingedly connected to said stick, stretchers 50 hingedly connected to said ribs, a runner slideable upon said stick, a plate attached to said runner, said plate being provided with a plurality of ears alternately disposed in opposite directions, a hinge ring locked in 55 position upon said plate by said ears, and means for hingedly connecting said stretchers with said ring.

16. An umbrella comprising a stick, a plurality of ribs, a hinge plate carried by said 60 stick and adapted to be moved thereon, a hinge ring associated with said plate, a plurality of ears carried by said plate and adapted to cooperate with said ring for retaining the same in position with respect to 65 said plate, and a plurality of stretchers having their outer ends hingedly connected to said ribs and their inner ends hingedly connected to said ring, said ears being adapted to function as seats for the inner hinged ends 70 of said stretchers.

17. An umbrella comprising a stick, a plurality of ribs hingedly connected to said 75 stick, a runner carried by said stick, said runner being provided with ears and a plurality of stretchers having their outer ends hingedly connected to said ribs and their inner ends hingedly connected to said runner, the inner hinged ends of said 80 stretchers being seated upon said ears.

18. An umbrella comprising a stick a plurality of ribs hingedly connected to said stick, a plurality of stretchers hingedly connected at their outer ends to said ribs, a runner carried by said stick, a plate associated with said runner and provided with a plurality of ears, a hinge ring associated with said plate and hingedly connected to the inner ends of said stretchers, certain of said ears being folded in one direction over said ring whereas the other of said ears is folded over said ring in an opposite direction and adapted to receive thereupon the inner hinge ends of said stretchers.

In testimony whereof, I have affixed my 95 signature.

JAMES REID.
